US00D835813S

(12) **United States Design Patent** (10) Patent No.: **US D835,813 S**
Lee (45) Date of Patent: **** Dec. 11, 2018**

(54) **BASEBOARD FOR A WALL PANEL**

(71) Applicant: **Chung Jong Lee**, Seoul (KR)

(72) Inventor: **Chung Jong Lee**, Seoul (KR)

(**) Term: **15 Years**

(21) Appl. No.: **29/589,196**

(22) Filed: **Dec. 29, 2016**

(30) **Foreign Application Priority Data**

Jun. 30, 2016 (KR) 30-2016-0032063
